CASKET, VAULT AND COVER HANDLING MECHANISM

Edward A. Meewes, Pico, Calif.

Application May 13, 1957, Serial No. 658,648

7 Claims. (Cl. 27—32)

This invention relates to mechanism for handling a casket, a vault into which the casket is fitted and a cover for the vault to effect sealed enclosure of the casket within the vault and when the vault is in a grave.

Each of the above items is a heavy and cumbersome unit and is difficult to handle. The labor of several men is ordinarily required for placing a vault within a grave, a casket first above the vault and then therewithin, placing a cover on the vault for enclosing the casket, and, finally, lowering the combined vault, casket and cover preparatory to filling in the earth around the combination unit. When it is realized that caskets are frequently quite heavy and often are made of metal, and that a vault and cover usually are made of cement of a thickness suitable to protect the casket enclosed thereby, it will be evident that manual handling of these units is, indeed, wasteful and consuming of labor and time.

An object of the present invention is to provide mechanism that can be manipulated by one person to accomplish the above-described handling and/or moving of the combined device.

Another object of the invention is to provide means for moving both a vault and a casket, relatively, so that the latter moves into the former and both together may be lowered into a grave, the movement starting with the casket in a position above the mouth of the grave, as when services are being conducted.

A further object of the invention is to provide means as above indicated by means of which a casket is lowered into a vault while the vault is being lowered into a grave.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes, preferred embodiments of the present invention, which are given by way of illustration or example only.

In the drawings, like reference characters designate similar parts in the several views.

Fig. 1 is a top plan view of vault and casket handling mechanism embodying a preferred form according to the present invention.

Fig. 2 is a side elevational view thereof, the vault and casket being shown in position preparatory to being lowered into a grave and the casket into the vault.

Fig. 3 is an enlarged cross-sectional view, as taken through the middle part of Fig. 2.

Fig. 4 is a similar view showing the vault and casket lowered partly into a grave and preparatory to receiving a vault cover.

Fig. 5 is an enlarged broken side view showing means for releasably connecting vault and casket lowering webbing to the mechanism.

2

Fig. 6 is a cross-sectional view of the means shown in Fig. 5.

A grave or cavity 15 is dug in the ground 16 in the usual way and, also, in the usual manner, a platform 17 is placed upon the ground so as to frame the grave. In the present instance, said platform mounts a pair of longitudinally arranged shafts 18, one on each side of the grave, the ends of said shafts being journaled in bearings 19 arranged in pairs at the opposite ends of the platform. As is common, two of these bearings are provided with drive means, the same being commonly connected by a cross shaft 20 that may be turned by a crank applied to either drive end 21. It will be realized that shaft 20 drives shafts 18 and that the latter may be driven in either direction, as desired. It will also be realized that a power-reversing drive may be provided for the shafts 18. These shafts turn in opposite directions so as to take up or pay out on cables 22 at each end, it being understood that said cables span across the grave 15 and may be used as slings by means of which a casket may be lowered into a grave in instances where vaults are not used.

It will be seen that, except for the cables 22, the grave opening is clear. The above-described and generally conventional means constitutes a power unit which is the base upon which the present mechanism is mounted.

The drawing shows a conventional vault 23 that usually comprises a rectangular receptacle made of cement and with wall thickness to insure against penetration of moisture. The same is open-topped and, with some clearance all around, is adapted to fit within the grave 15. A conventional lid or cover (not shown) may be provided for said vault. The enclosure comprising said vault and cover is adapted to house a casket 25. By applying grouting, mortar and the like between the vault and lid to cover the seam therebetween, the casket may be sealed in and the same is protected as hereinabove indicated.

In the present case, the cables 22 comprise vault-suspending slings and by rotation of the shafts 18, the vault may be lowered into or raised out of the grave.

According to this invention, the above-described means is provided, generally, with means 26 to lower the casket 25 into the vault 23, and means 27 to separably connect the means 26 to the drive shafts 18 whereby said means 26 may be easily removed after serving its operational purpose.

In Figs. 1 to 4, the means 26 is shown as bands or webs 29 that span between the shafts 18, one adjacent each end of said shafts and preferably inward of the cables 22. Said webs are trained across the open top of the vault 23 and serve to support a casket 25 and to hold the same upwardly outward of the interior of the vault.

The means 27 is best shown in Figs. 5 and 6 and, while the same may comprise any suitable quick detachable means, is here shown as a clamp bar 30 on studs 31 affixed to each shaft 18, each said bar having slots 32 engaged with said studs so the bar may be dislodged from the studs to enable detachment of that end of a web 29 that is clamped by the bar. The means 27 may be provided on one or both shafts 18, although one is sufficient to enable removal of a web from between a vault and a casket after the latter has been lowered into the former.

It will be seen, by comparing the positions of the vault 23 and casket 25 in Figs. 3 and 4, that, from a position one above the other and respectively supported by cables 22 and webs 29, said vault moves into the grave 15 while the casket moves into the vault when the shafts 18 are rotated in a direction to slacken off on said cables and webs. Thus, casket 25 moves faster and a further distance than does the vault 23. After the casket has achieved a bottoming position in the vault and before

the latter is finally fully lowered into the grave, the vault cover may be applied. Thereafter, the casket-provided vault may be fully lowered in the ordinary way.

While the foregoing has illustrated and described what are now contemplated to be the best modes of carrying out my invention, the constructions are, of course, subject to modification without departing from the spirit and scope of the invention. It is, therefore, not desired to restrict the invention to the particular forms of construction illustrated and described, but to cover all modifications that may fall within the scope of the appended claims.

Vaults vary in design and the present means may, without essential change, handle air seal types of vaults as well.

Having thus described my invention, what I claim and desire to secure by Letters Patent is:

1. In an apparatus having a single pair of parallel longitudinal shafts adapted to be driven in either direction, as desired, and disposed one on either side of a grave, a pair of cables connected to and spanning between said shafts adjacent each end thereof and adapted to support a vault above the grave, and means connected to the shafts located between the cables and spanning between said shafts in supported engagement with the vault to support a casket above said vault, rotation of the shafts, in one direction, increasing the spanning lengths of both the cables and the spanning means simultaneously whereby increased length of the cables causes the vault to lower into the grave and simultaneous increased length of the spanning means causes the casket to lower into the vault during mentioned lowering of the vault.

2. In an apparatus having a single pair of parallel longitudinal shafts adapted to be driven in either direction, as desired, and disposed one on either side of a grave, a pair of cables connected to and spanning between said shafts adjacent each end thereof and adapted to support a vault above the grave, and means connected to the shafts located between the cables and spanning between said shafts in supported engagement with the vault to support a casket above said vault, rotation of the shafts, in one direction, increasing the spanning lengths of both the cables and the spanning means simultaneously whereby increased length of the cables causes the vault to lower into the grave and simultaneous increased length of the spanning means causes the casket to lower into the vault during mentioned lowering of the vault, said latter means comprising two bands connected to the shafts and spanning across the top of the vault.

3. In an apparatus having a single pair of parallel longitudinal shafts adapted to be driven in either direction, as desired, and disposed one on either side of a grave, a pair of cables connected to and spanning between said shafts adjacent each end thereof and adapted to support a vault above the grave, and means connected to the shafts located between the cables and spanning between said shafts in supported engagement with the vault to support a casket above said vault, rotation of the shafts, in one direction, increasing the spanning lengths of both the cables and the spanning means simultaneously whereby increased length of the cables causes the vault to lower into the grave and simultaneous increased length of the spanning means causes the casket to lower into the vault during mentioned lowering of the vault.

vault, said latter means comprising two bands connected to the shafts and spanning across the top of the vault, at least one end of each band being provided with a separable connection with one of the shafts.

5. In an apparatus having a single pair of parallel longitudinal shafts adapted to be driven in either direction, as desired, and disposed one on either side of a grave, a pair of cables connected to and spanning between said shafts adjacent each end thereof and adapted to support a vault above the grave, the combination with said shafts of a casket-supporting webbing adjacent each end thereof connected to and spanning between the shafts across the top of the vault, said webbing being wrapped around each shaft in a direction to foreshorten as the cables foreshorten and to lengthen as the cables lengthen, rotation of the shafts in one direction increasing the spanning lengths of the cables and webbing simultaneously whereby the vault lowers into the grave on the slack of the cables as the same lengthens and the casket lowers into the vault on the slack of the webbing during lowering of the vault.

10. In an apparatus having a single pair of parallel longitudinal shafts adapted to be driven in either direction, as desired, and disposed one on either side of a grave, a pair of cables connected to and spanning between said shafts adjacent each end thereof and adapted to support a vault above the grave, the combination with said shafts of a casket-supporting webbing adjacent each end thereof connected to and spanning between the shafts across the top of the vault, said webbing being wrapped around each shaft in a direction to foreshorten as the cables foreshorten and to lengthen as the cables lengthen, rotation of the shafts in one direction increasing the spanning lengths of the cables and webbing simultaneously whereby the vault lowers into the grave on the slack of the cables as the same lengthens and the casket lowers into the vault on the slack of the webbing during lowering of the vault, at least one end of each webbing being provided with a separable connection with one of the shafts.

15. In an apparatus having a single pair of parallel longitudinal shafts adapted to be driven in either direction, as desired, and disposed one on either side of a grave, a pair of cables connected to and spanning between said shafts adjacent each end thereof and adapted to support a vault above the grave, the combination with said shafts of a casket-supporting webbing adjacent each end thereof connected to and spanning between the shafts across the top of the vault, said webbing being wrapped around each shaft in a direction to foreshorten as the cables foreshorten and to lengthen as the cables lengthen, rotation of the shafts in one direction increasing the spanning lengths of the cables and webbing simultaneously whereby the vault lowers into the grave on the slack of the cables as the same lengthens and the casket lowers into the vault on the slack of the webbing during lowering of the vault, at least one end of each webbing being provided with a separable connection with one of the shafts.

20. In an apparatus having a single pair of parallel longitudinal shafts adapted to be driven in either direction, as desired, and disposed one on either side of a grave, a pair of cables connected to and spanning between said shafts adjacent each end thereof and adapted to support a vault above the grave, the combination with said shafts of a casket-supporting webbing adjacent each end thereof connected to and spanning between the shafts across the top of the vault, said webbing being wrapped around each shaft in a direction to foreshorten as the cables foreshorten and to lengthen as the cables lengthen, rotation of the shafts in one direction increasing the spanning lengths of the cables and webbing simultaneously whereby the vault lowers into the grave on the slack of the cables as the same lengthens and the casket lowers into the vault on the slack of the webbing during lowering of the vault, at least one end of each webbing being provided with a separable connection with one of the shafts.
